INVENTOR

Charles Sneider,
By C. M. Alexander,
Attorney.

UNITED STATES PATENT OFFICE.

CHARLES SNEIDER, OF NEW YORK, N. Y., ASSIGNOR TO PHILIPP HAKE, OF HOBOKEN, NEW JERSEY.

ENVELOPE OR FOLDING CARD.

SPECIFICATION forming part of Letters Patent No. 295,450, dated March 18, 1884.

Application filed October 18, 1883. (No model.)

To all whom it may concern:

- Be it known that I, CHARLES SNEIDER, a citizen of the United States, residing at New York, in the county of New York and State of New York, have invented certain new and useful Improvements in Envelopes or Folding Cards, of which the following is a specification, reference being had therein to the accompanying drawings.
- 10 This invention relates to certain improvements in envelopes of that class in which it is not desirable to cement the parts; and it is specially designed for circulars, wedding and other invitations, and for other like purposes.
- 15 The invention has for its objects to provide certain improved means whereby the parts of the envelope may be fastened together in a neat and ornamental manner, so that they can be readily opened without destroying or de-
- 20 facing any part of the envelope, and refastened when desired, as more fully hereinafter specified.
- 25 In the drawings, Figure 1 represents a view of the blank from which my improved envelope is formed. Fig. 2 represents a view of the envelope complete and fastened; and Fig. 3 represents a sectional view of one of the flaps, taken on the line $x x$ of Fig. 1, showing a portion of the fastening devices.
- 30 The letter A indicates a blank constructed of card-board, paper, or other material sufficiently stiff and rigid to permit portions of the same to be stamped up into the form of hooks, as hereinafter explained.
- 35 The blank may be of any suitable shape, as taste or fancy may dictate, and is provided with suitable folding flaps, which may be secured together by a lacing-cord or its equivalent, as more fully hereinafter shown.
- 40 In the present instance the blank consists of a rectangular body, a , having at the lower half lateral extensions b , which form the folding flaps before mentioned. The upper half of said body is arranged to fold over the lower half on the line c , and the lateral extensions to fold toward each other over the folded upper half on the lines $d d$. Near the edges of

the flaps the material of the envelope is cut or partially perforated, forming a series of tongues, e , which are bent outward, so as to 50 constitute a series of fastening-hooks, over which the lacing g may be passed, as shown in Fig. 2 of the drawings.

The blank, as before stated, may be made of any suitable material, and it is preferably 55 stamped or cut in one piece entire from a sheet of the material.

The lacing may consist of a simple cord or wire, or, in the case of a fancy envelope or card—such as required for weddings, invitations, and the like—of an ornamental silk cord or ribbon, which may be provided with a rosette or other ornamental device, by which it may be secured to the envelope, and with tassels or other ornaments at the free ends. 65

The envelope itself may be suitably ornamented, and may constitute the card or circular, the invitation or other matter being written or printed on the inside of the body; or the envelope may be left plain, as shown 7c in Fig. 1 of the drawings, and employed to hold an invitation or other matter, or a separate card or paper.

The manner of folding and securing the envelope will be apparent from the above description, in connection with Fig. 2 of the drawings, and hence further description in that direction is deemed unnecessary. 75

Having thus described my invention, what I claim, and desire to secure by Letters Patent, is—

An envelope or folding card provided with folding flaps having struck-up hooks near their edges, in combination with a lacing adapted to be secured around said hooks, to 85 hold the parts of the envelope together, substantially as specified.

In testimony whereof I affix my signature in presence of two witnesses.

CHAS. SNEIDER.
